UNITED STATES PATENT OFFICE.

DANIEL J. McCARTHY, OF WILKINSBURG, PENNSYLVANIA, ASSIGNOR TO UNION SWITCH & SIGNAL COMPANY, OF SWISSVALE, PENNSYLVANIA, A CORPORATION OF PENNSYLVANIA.

MEANS FOR AUTOMATICALLY CONTROLLING THE SPEED OF RAILWAY-TRAINS.

No. 867,522.

Specification of Letters Patent.

Patented Oct. 1, 1907.

Application filed April 25, 1907. Serial No. 370,231.

To all whom it may concern:

Be it known that I, DANIEL J. McCARTHY, of Wilkinsburg, Allegheny county, Pennsylvania, have invented a new and useful Means for Automatically Controlling the Speed of Railway-Trains, of which the following is a full, clear, and exact description, reference being had to the accompanying drawings, forming part of this specification, in which—

Figures 1, 2 and 3 are diagrams illustrating one form 10 of my invention; Fig. 4 is a detail sectional view of one form of operating device or controller; and Fig. 5 is a diagram showing another form of my invention.

My invention has for its object the automatic control and regulation of the speed of a locomotive or 15 train at points along the right of way where it is deemed unsafe to exceed a certain predetermined speed, as at switches, curves, or in running by distant signals.

My invention consists in the provision of means, carried in part by the locomotive or train, and in part 20 located along the track at points where the speed is to be controlled, whereby an electric current is induced in a circuit on the locomotive or train, which circuit includes a brake operating device or controller arranged to apply the brakes to either stop the train or 25 check its speed.

My invention also consists in the novel construction, arrangement and combination of parts all substantially as hereinafter described.

Referring to the accompanying drawings, the numeral 2 designates a series of magnet poles which are wound with coils 3 in such a manner as to produce opposite polarity of alternate poles. A series of these electro-magnets are placed adjacent to the track wherever the speed is to be regulated or controlled. 35 Thus, in Fig. 1 I have shown one series adjacent to a branch or turnout, and another series on an approach to the track curve 4.

5 designates an induction coil which is wound upon a suitable magnetic core mounted upon the locomotive 40 or car of a train in such a manner as to travel in close proximity to the polar faces of the magnets 2 when the locomotive or car is passing the same. Included in the circuit 6 of this coil is a device or controller 7, which operates the controlling mechanism of the locomotive, which may be either the brakes, or the throttle valve, or both. As the coil passes these electro-magnets, an electro-motive force is generated in the coil, which causes a current to flow through and operate the controller 7, as more fully hereinafter described.

50 It is advantageous to have different speed limits at different points on the right of way, and this may be accomplished in the following manner:—The controller 7 which operates, when energized, the controlling mechanism of the locomotive, may be so de-

signed as to operate only at an electro-motive force 55 above a certain predetermined value, being inoperative by an electro-motive force of any lower value. As the electro-motive force generated in a conductor cutting lines of force, is proportional to the rate of cutting, it follows that the electro-motive force which will be 60 generated in the coil 5 as it passes through the magnetic field produced by the electro-magnets, will depend upon the rate at which it cuts the magnetic flux of this field. This can be expressed by the formula

$$E = \frac{N}{10^8 X t}, \quad 65$$

in which E equals the electro-motive force to be generated in the coil 5 necessary to operate the controller 7; N the number of lines of force cut by said coil; and 70 t the time in seconds taken to cut the lines of force N. If E remains constant, any change in N will make a corresponding change in t; if the value of N is lowered, the value of t will also be correspondingly lowered, and vice versa; so that if the value of N is lowered, 75 the coil 5 will have to pass over the pole faces of the magnets in a correspondingly shorter time in order to have the necessary electro-motive force generated therein to operate the controller 7. This allows a higher speed to the motor or car carrying this coil. If 80 the value of N is raised, the speed at which the coil 5 travels over the magnets will be correspondingly slower in producing the same electro-motive force, therefore permitting a lower speed for the locomotive or car. Thus, in the arrangement illustrated in Fig. 1, supposing that the desired speed at which the train shall 85 pass the switch 8 is less than its speed in passing the curve 4, the magnetic flux of the magnets adjacent to the switch 8 will be higher than that at the magnets at the approach to the curve. This may be accomplished 90 by altering the capacity of the battery 9, which energizes the magnets; or, if the source of current supply is from a line, the number of ampere turns may be proportioned according to the desired flux. If the speed of the train in passing over the magnets does not exceed the allowable limit, the controller mechanism will not in any way be operated, owing to the fact that the required electro-motive force has not been generated in the coil 5.

It may be desirable to have different speed limits 100 for different rolling stock equipment; for instance, a safe speed for a passenger train through the curve 4 might be an unsafe speed for a freight train. This condition can be governed by equipping the freight locomotive with a controller 7 which will work at a lower 105 electro-motive force than that of the controller on passenger trains; or by changing the number of turns in the coil 5 the same result may be obtained, a smaller

number of turns permitting a higher speed, and a greater number of turns a lower speed.

It will be noted that the current generated in the coil 5 will be an alternating current, the frequency of which will depend upon the number of poles passed over in a given time, or equal to the number of pairs of poles passed over per second, as expressed by the following formula

$$10 \quad N = \frac{P}{2S},$$

in which P equals the number of poles, S the time in seconds in which the coil 5 moves over these poles, and N the frequency per second. If the frequency is constant, any change in P will make a corresponding change in S. This fact may also be taken advantage of to regulate the speed of the locomotive or train by so designing the controller 7 that it will operate only on a frequency higher than a certain predetermined frequency. The changing of the number of poles in a given space over which the coil 5 passes, will also permit different speeds at various points on the right of way. That is to say, any desired speed limit can be maintained by placing the proper number of poles in a given space, corresponding to the speed at which the coil 5 is to pass over them to produce the proper frequency for the operation of the controller 7.

In Fig. 5 I have shown another means of operating the controller 7 by an alternating current. In this figure 10 and 11 designate the two track rails. 12 is a conductor placed adjacent to one of the track rails and divided into short separated sections. Alternate ones of these sections are connected together by means of conductors 13, and one of the end sections is connected by a conductor 14 with one terminal of a battery 15, whose other terminal is connected to one of the track rails. The locomotive or car carries a transformer, whose primary coil 16 is connected to the track rails through the car wheels 17 and to the conductors 12 through a sliding contact 18. The secondary coil 19 of this transformer is in the circuit of the controller 7. As the sliding contact 18 moves over the conductors 12 a pulsating current is sent through the primary coil 16 of the transformer, which induces an alternating current in the secondary 19, the frequency of which depends upon the rate of speed at which the contact 18 passes over the conductors 12.

In Fig. 4 I have shown one form of the controller 7. 20 designates a coil either of a solenoid or other form of magnet, which is connected in the circuit of the induction coil 5 or with the secondary coil 19 of the transformer of Fig. 5, as before described. The armature core 21 of this coil 20 is connected to a plunger 22 working in a valve casing 23 against a spring 24. The normal position of this plunger is as shown in Fig. 4. When the coil 20 is energized by a current to which it is responsive, the plunger 22 is moved against the spring 24 into a position where its port 25 will connect the port 26 with the cylinder chamber 27. The port 26 is connected with the train line pipe of the air brake system. 60 In the cylinder chamber 27 is a piston valve 28, which is normally held by a spring 29 in position to close an exhaust port 30.

When the piston is operated as above described to

connect the port 26 with the cylinder chamber 27, the pressure from the train-pipe enters said chamber above the piston of the valve and moves the latter against the spring 29 to open the exhaust port 30. This permits air to exhaust from the train line, and causes an application of the brakes. The plunger 22 is locked in this position by means of the spring-pressed pawl 31 which engages the notch or recess 32 in the plunger.

33 designates a cylinder which is connected to the valve casing 23, in which is a piston 34 which is normally held towards the outer end portion of the cylinder against a spring 35, by means of air pressure admitted thereto by way of the port 26, the port 36 in the plunger and the port 37, leading from the plunger to the cylinder. Extending through this port 37 into the cylinder is a rod 38 which also extends through a slot in the plunger into contact with the pawl or dog 31. When the pressure of the train line is reduced to the proper amount, the valve 28 is reseated by the spring 29, but will be again opened if the pressure in the chamber 27 rises enough to compress the spring 29, thus insuring the reduction of the train line pressure to the desired point at which it will remain constant. The amount of the reduction may be governed by adjusting the spring 29.

When the plunger 22 has been operated as above described, the port 36 is moved so as to overlap an exhaust port 39 in the valve casing, thereby permitting air to exhaust from the cylinder 33 by way of the ports 36, 37 and 39. This reduces the pressure in cylinder 33 and permits the spring 35 to force the piston 34 into contact with the end of the rod 38. This forces the pawl 31 out of engagement with the plunger 22 and permits the spring 24 to restore said plunger to its normal position. By altering the size of the port 39, the time taken by the piston 34 to complete its stroke can be made longer or shorter, as desired, thereby governing the length of time during which the brakes are applied.

The system herein described does not permit of any operation of its parts by the engine man or other operator on the train. The only operation which the engine man is required to make, is to place the brake valve handle in the release position so as to release the brakes after they have been applied in the manner above described. It is immaterial whether this lever is put into releasing position before or after the application of the brakes takes place, since the brakes cannot be released until the piston 34 has completed its stroke and released the plunger 22. It will thus be seen that my invention provides means whereby the speed of a locomotive or train can be automatically controlled at any desired point along the right of way, or within any desired limits, different speeds being permissible for different trains, if desired.

My invention is susceptible to various modifications by those skilled in the art. Thus, any suitable means may be provided for inducing a current in the circuit of the controller; and the latter can consist of any form of electromagnetic device suitable for the purpose. This controller may be made to operate directly upon the brake-applying valves as shown in Fig. 4, or it may be connected directly or indirectly to intermediate valves. It may also be connected to the throttle

valve of the engine, or to both the throttle valve and to a brake-applying valve.

What I claim is:—

1. In speed-controlling mechanism for trains, a brake-controlling valve, a magnet for opening said valve, an energizing circuit for said magnet on the locomotive or train, and means whereby the movement of the train beyond a predetermined speed is caused to generate a current of proper character to energize said circuit at predetermined 10 places along the road; substantially as described.
2. In speed-controlling mechanism for trains, a speed-controlling device, an electro-magnetic device for operating the same, and responsive only to a current having a frequency above a predetermined limit, and inductive means 15 for generating an alternating current for actuating said device at predetermined places along the road, substantially as described.
3. In speed-controlling mechanism for trains, a speed-controller, an electro-magnetic device for operating the 20 controller to reduce the speed of the train, and means for inducing a current in the circuit of said device, said means being carried in part by the train and in part located along the trackway, said electro-magnetic device being responsive only to a current having a frequency above a 25 certain predetermined frequency; substantially as described.
4. In apparatus for the purpose described, a speed controller, an electro-magnetic means for operating said controller to reduce the speed, means for inducing current in 30 the circuit of said device by the movement of the train past predetermined points, and means for automatically returning the speed controller to said normal position; substantially as described.
5. In apparatus for the purpose described, a speed-controlling device, an electro-magnetically operated actuating device therefor, an induction coil in the circuit of said device, and means along the right of way for inducing a 35

circuit in said coil of a certain frequency at a predetermined speed of the train; substantially as described.

6. In apparatus of the character described, a speed controlling device, electro-magnetic operating means therefor, an induction coil in the circuit of said means, and electromagnets adjacent to the right of way adapted to induce a current in said coil and spaced at such distances as to cause a given frequency to such current at a given speed 45 of the train; substantially as described.

7. In apparatus of the character described, a speed controlling device, an electro-magnetically operated actuator therefor arranged to be moved by a current of a certain character, and means along the trackway for inducing a 50 current of the proper character to move the actuator when the speed of the train reaches a predetermined limit; substantially as described.

8. A speed controlling device for trains, consisting of a valve chamber connected with the train brake system and 55 having an escape opening, valve means for controlling said opening, an electro-magnetic device for actuating said valve means in one direction, springs for actuating the valves in the opposite direction, a lock for holding the valve means in open position, and means for releasing the 60 lock after a predetermined time interval; substantially as described.

9. A speed controlling device connected with the brake system of a locomotive or train, and having an escape opening, valve means controlling said opening, an electro-magnetic device for operating the valve means in one direction, spring means for operating the valve means in the other direction, a lock for the valve means, and a pneumatic device for releasing said lock after a predetermined time interval; substantially as described. 65

In testimony whereof, I have hereunto set my hand.

DANIEL J. McCARTHY.
